DESCRIPTION

FIG. 1 is a perspective view of a ellipsoidal shaped display showing our new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a sectional view of the interior thereof taken along line 8-8 of FIG. 2;

FIG. 9 is the same sectional view thereof shown in FIG. 8 displaying a static image;

FIG. 10 is the same sectional view shown in FIG. 8 displaying an animated or moving image; and,

FIG. 11 is a perspective view thereof shown in use.

The lines shown broken away and the brackets used in FIGS. 1 and 4-10 indicate that the length of the ellipsoidal shaped display is indeterminate, and all broken lines shown in the disclosure represent environment only and form no part of the claimed design.

The claimed ellipsoidal shaped display has a curved viewing plane visible on the interior of an ellipsoidal shape large enough for a person to walk through and view.
